UNITED STATES PATENT OFFICE.

CLARK HALL AND WILLIAM HENRY WRIGHT, OF EAST FARNHAM, QUEBEC,
CANADA.

SUGAR-SAP EVAPORATOR.

SPECIFICATION forming part of Letters Patent No. 415,635, dated November 19, 1889.

Application filed February 1, 1889. Serial No. 298,312. (No model.) Patented in Canada March 7, 1888, No. 28,644.

To all whom it may concern:

Be it known that we, CLARK HALL and WILLIAM HENRY WRIGHT, residing at East Farnham, in the Province of Quebec, Canada, have 5 invented certain new and useful Improvements in Sugar-Sap Evaporators; (for which we have obtained a patent in Canada, No. 28,644, dated March 7, 1888;) and we do hereby declare the following to be a full, clear, and 10 exact description of the invention, such as will enable others skilled in the art to which it appertains to make and use the same.

Our invention consists of the combination, with an evaporating-pan provided with a 15 cross-partition having openings at each end and compartments on each side of said partition communicating at alternate ends, of, first, an elevated heater, in which the sap is heated to the boiling-point by the waste 20 steam before being introduced into the evaporator; and, second, of a reversible spout connected with the heater, whereby the circulation of the sap may be reversed at pleasure during the process of evaporation.

25 The object of our invention is to provide increased evaporating-surface to prevent the accumulation of niter on the bottom of the siruping-down compartment, and to provide an evaporator which can easily be kept clean, 30 and thus avoid the risk of "burning" when niter is beginning to accumulate on the bottom of the pan.

Referring to the drawings, Figure 1 is a 35 side perspective view of an evaporator embodying our improvements, and Fig. 2 is an end perspective view of the same.

The evaporating-pan A is made of tin, galvanized iron, or other suitable material, and is divided into two parts or compartments by 40 the cross-partition B. The first part or compartment of this evaporating-pan is again subdivided by an odd number of longitudinal guides or partitions C, which have openings D at alternate ends, for the purpose 45 of communication between the sub-compartments thus formed. The guides or partitions nearest the sides of the evaporating-pan have their openings at the end opposite the cross-partition B. The larger portion of the 50 bottom of the rear half of the evaporating-

pan is provided with longitudinal recesses or channels E, which extend nearly the whole length of this said rear part, and also with longitudinal partitions or guides F, corresponding in number with the guides C in the 55 front part. These guides F are provided with openings G at alternate ends for the purpose of communication between the sub-compartments thus formed. The two outside sub-compartments M M' of this rear half 60 of the evaporator have plain flat bottoms, each divided into two parts by partitions H H', having holes or openings I I', which are closed by slides K K', when necessary. The cross-partition B is provided with openings 65 L L', at its opposite ends, to permit the flow of sap from and to each half of the evaporator alternately. Openings or pipes are provided at P P', for drawing off the sirup when ready.

70 The heater N, shaped like a small ordinary evaporator, with plain guides n, is placed over the inner end of the rear half of the evaporator, resting upon the guides F F, to which it is secured, and next to the cross-partition B, to 75 which it is also secured. It is provided with an opening, in which is fitted a movable or reversible spout O, for conducting the heated sap to the one or the other of the smaller divisions of the sub-compartments M M', as 80 may be desired.

70 The mode of operation is as follows: The sap, conveyed in the usual manner to the heater N, is heated to boiling-point by the steam arising from the boiling sap in the 85 rear half of the evaporator and conveyed by the spout O to either of the small divisions of the sub-compartments M M'. Referring to Fig. 2, it will be seen that the sap is conveyed to the small divisions of the compartment M'. The slide K' being closed and the slide K open, the circulation is in the direction of the arrows, passing from the rear to the front half of evaporator by the opening L, and again by L' to sub-compartment M', 90 from whence it passes in the form of sirup by the pipe P'. If niter should appear to be forming on the bottom of sub-compartment M', the circulation of sap must be reversed 95 by moving the spout O over to the small 100

division of sub-compartment M, closing the slide K and opening K', which will be readily comprehended on reference to Fig. 1. The sap will then move in the direction opposite to that indicated by the arrows in Fig. 2, wash whatever niter may have formed on the bottom of M', and pass off as sirup at the opening P.

We make no claim to the evaporator as such, for we are aware that that is not new; but

What we claim as our invention, and desire to secure by Letters Patent, is—

The hereinbefore-described evaporating apparatus comprising the evaporating-pan provided with the cross-partition B, dividing the evaporating-pan into two compartments, and having openings at its opposite ends, the longitudinal partitions C, dividing the front compartments of the pan into a series of sub-com-

partments, and having openings D at alternate ends, the longitudinal channels E, in the bottom of the rear compartment of the evaporating-pan, the partitions F, subdividing the said rear compartment, the end compartments M M', having plain bottoms, the partitions H H', again subdividing compartments M M', and having openings I I', and the slides K K', for closing the openings I I', the elevated heater N, placed over the rear compartment, and the reversible spout O, all combined and operating substantially as and for the purposes described.

In testimony whereof we affix our signatures in presence of two witnesses.

CLARK HALL.

WILLIAM HENRY WRIGHT.
